John C. King, Boston, Massachusetts
Letters Patent No. 15 dated January 31, (1843.) 1844

The Schedule referred to in these Letters Patent and making part of the same. —

To all Persons whom it may concern.

Be it known, that I John C. King, the undersigned, of Boston, in the County of Suffolk and State of Massachusetts, Sculptor, have invented, a new and original design for a bust of Robert Burns the Poet of Scotland, a drawing of which is hereto annexed.

In testimony Whereof, I the said John C. King, hereto subscribe my name in the presence of the Witnesses whose names are hereto subscribed on the seventeenth day of October A.D. 1843, at said Boston.
